HIS ATTORNEY.

UNITED STATES PATENT OFFICE

2,341,708

SAFETY DEVICE FOR FIRE EXTINGUISHERS

Fred Fredriksen, Chicago, Ill.

Application January 14, 1943, Serial No. 472,395

5 Claims. (Cl. 169—30)

This invention relates to a safety device for fire extinguishers and has as its principal object to provide a safety device which is simple in construction, economical in manufacture and highly efficient in use.

It is another object of this invention to provide a means for having a visible check against any illegal or unwarranted tampering with fire prevention equipment.

Another object of my invention is to provide a removable seal whereby to completely guard the hose connection and nozzle of an extinguisher and yet permit immediate use thereof without the use of tools or instrumentalities other than human hands.

Still another object of this invention is to provide a durable covering for vital portions of a fire extinguisher which covering itself also provides a record bearing means which is at all times visible upon the most cursory inspection.

Other objects will appear more fully hereinafter.

The invention consists in the novel combination and arrangement of parts to be hereinafter described and claimed.

The invention will be best understood by a reference to the accompanying drawing in which:

Fig. 1 is a perspective view of a pressure type fire extinguisher with the preferred form of my new safety device associated therewith;

Fig. 2 is a blank of the preferred form of my new safety device as seen on the inside face thereof before folding and assembly;

Fig. 3 is a fragmentary vertical sectional detail view through the safety device and extinguisher as seen along line 3—3 in Fig. 1;

Fig. 4 is a fragmentary horizontal sectional detail view through my new safety device as seen along line 4—4 in Fig. 1;

Fig. 5 is a side elevational view of a pump type extinguisher showing a modified form of my safety device associated therewith;

Fig. 6 is a fragmentary perspective view of another form of pump type extinguisher showing the modified form of safety device illustrated in Fig. 5 associated therewith;

Fig. 7 is a fragmentary perspective view of a modification of the lower end of my new safety device; and

Fig. 8 is a cross-sectional detail view of the sheath embodied in the invention.

As seen in the drawing my safety device is adapted for use on fire extinguishers of the conventional and well-known type as a protective

measure to at all times indicate the readiness of the equipment for operation. In practice, equipment such as these fire extinguishers are placed on racks in convenient places in a building so that they may be available when an emergency arises. With such equipment openly displayed there is a possibility of their being tampered with; hoses torn; objects inserted into the nozzle by pranksters hence plugging the outlet; and it is not uncommon to find that the entire contents of the extinguisher tank have been removed without the proprietor being aware of such fact. Negligence and complacency on the part of the building management or of persons responsible for the workability of such equipment has occasioned a skipping of their periodical inspection and hence in some instances the equipment has proved faulty or totally useless when an actual application of its use is required. It is a well-known fact that an early application of fire extinguishing solutions prevent further damage by fire and it is to this end that my new safety device serves its purpose.

25 The safety device is preferably, though not necessarily, constructed from a single sheet of paper 10 of a suitable weight and thickness to prevent accidental bursting of the fibre structure. As seen in Fig. 2 the paper is cut in blanks such as the blank 11 to provide a front portion 12 and a back portion 13 joined by a pleat or double fold web 14 which when folded in the manner shown will dispose the free edge 15 of the back portion 13 in a position to overlie a flap 16 on the complementary edge of the front portion 12. The free edge 15 is then attached to the flap 16 by stitching 17 or the like to form an elongated sheath 18. The blank 11 has a bottom flap 19 which is folded around and over the back portion 13 to which it is attached by stitching 17. A portion 20 of the front wall 12 extends beyond the sheath proper and has formed integrally therewith a collar member 21 by which the sheath 18 is attached to a fire extinguisher.

35 In use the safety device shown in Figs. 1 to 4 inclusive is mounted on a pressure type fire extinguisher generally indicated at 22 and having a tank or container portion 23 with an outlet through an elbow connection 24 formed thereon and connected to a flexible conductor or hose 25 with a nozzle 26 at its free end. The hose 25 is inserted into the sheath 18 with the nozzle 26 well guarded down in the bottom of the sheath, the upper edge 32 of the back portion 13 being well above the upper end of the hose 25 and in

the crevice of the elbow 24 so that the hose 25 cannot be removed without lowering the sheath 18. The pressure type fire extinguisher 22 has an open end 27 adjacent the outlet 24 and this open end 27 is formed by a neck portion 28 having threading 29 thereon. The collar member 21 is mounted on the threaded neck 28 against a shoulder 30 on the tank 23 and is held in place by the conventional filler cap 31 which is threaded down tight over the open end 27 to seal the same.

With the safety device thus secured on the extinguisher 22 it is impossible for anyone to tamper with the hose 25 or nozzle 26 without removing or tearing the sheath 18. To facilitate a quick removal of the sheath 18, should necessity require, there is cut into the portion 20 a series of perforations 33 along a line coinciding with the peripheral margin of the collar 21. When the use of the extinguisher is required the sheath with hose therein is raised to a substantial horizontal plane and the sheath ripped away from the collar along the perforations 33 and the sheath withdrawn from around the hose. It is an object of this invention to provide a safety device with a surface capable of receiving printed matter as seen in Fig. 7 which printed matter can be applied while the safety device is still in the form of the blank 11 before assembly. A lead seal 34 is provided between the filler cap 31 and the portion 20 closely adjacent the perforations 33 so that no one can remove the cap 31 and empty the container 23 of its contents without a destruction of the safety device which upon unscrewing of the filler cap 31 will be torn along the perforations 33 as the lead seal 34 is pulled by the filler cap, the wire 33' of this seal 34 being passed through an opening 34' formed in the portion 20.

It is therefore apparent that I have provided a novel guard for fire extinguishers whereby a most cursory examination will reveal whether or not the extinguisher has been tampered with. Also by reason of the publication of the inspection date and signature of the inspector right on the front face of the safety device, there is an assurance that persons responsible for the condition of fire extinguishers in a particular building will be more careful and positive in their duty of inspection.

In cases of the pump type extinguishers 42-43 as shown in Figs. 5 and 6 the collar 21 is severed at a point along the long axis of the front face 12 on the side of the collar farthest removed from the connecting portion 20 to provide a modified collar 35 so that the two loose ends 36 of the severed collar can be inserted through the handle 37 of the pump type extinguisher and be overlapped and joined by a common staple 38, paper fastener or other such well-known permanent fastener to anchor the sheath to the fire extinguisher. With this type of collar 35 an upward stroke of the pump handle 37 will rip the collar 35 away from the sheath 18 along the perforations 33 thus destroying the safety device and permitting removal of the hose 25 from the sheath.

While the length of hose 25 for conventional fire extinguishers is standard it is contemplated that the sheath 18 may be made longer than standard size as is the sheath 39 shown in Fig. 7 in which event should the hose length be shorter than such long type sheathes 39, by reason of the unpredictability of the lengths of hoses, the sheath 39 may be folded back so that

the nozzle is always close to the bottom of the sheath. In folding the sheath 39 back as shown in Fig. 7 the free end thereof is fastened to the back of the sheath by means of paper fasteners such as the wire staples 40.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. The combination of a fire extinguisher having a flexible conduit extending therefrom, with a safety device comprising a sheath for surrounding and enclosing said flexible conduit, a collar integral with said sheath and adapted to be affixed to a portion of the fire extinguisher, means to secure said collar to said portion to maintain said sheath in relative position with respect to said flexible conduit, said collar having perforations formed therein at its point of juncture with said sheath to facilitate removal of the latter from around said flexible conduit without removal of said collar.

2. The combination of a fire extinguisher having a flexible conduit extending therefrom, with a safety seal comprising a paper sheath adapted to receive said flexible conduit to completely enclose the same, an anchoring portion extending above the open end of said sheath, said safety seal being perforated at the point of juncture of said anchoring portion and said sheath, means securing said anchoring portion to said fire extinguisher, and means affixing said anchoring portion to a movable portion of said fire extinguisher whereby when the movable portion is moved relative to said fire extinguisher said anchoring portion will be severed from said sheath.

3. The combination of a fire extinguisher having a flexible conduit extending therefrom, with a safety seal comprising a sheet of fibrous material formed to provide an elongated bag adapted to be drawn over said flexible conduit to completely enclose the same, a portion of said sheet extending from the open end of said bag and having an anchoring portion formed integrally therewith and being perforated at the line of juncture with said anchoring portion, means to secure said anchoring portion to said fire extinguisher whereby to maintain said bag in relative position on said flexible conduit and permit of facile removal therefrom by tearing.

4. The combination of a fire extinguisher having a flexible conduit extending therefrom, with a safety seal comprising a sheet of fibrous material formed to provide an elongated bag adapted to receive printed matter, said elongated bag having an open end through which said flexible conduit is insertable into said bag to completely encase said flexible conduit, one wall of said bag extending beyond the open end of said bag and having an anchoring portion formed integrally therewith, means for securing said anchoring portion to said fire extinguisher, means for connecting said anchoring portion to a movable element of said fire extinguisher said anchoring portion having perforations formed therein at its point of juncture with said one wall of said bag

to facilitate severance of said anchoring portion from said bag when the movable element of fire extinguisher is moved.

5. The combination of a fire extinguisher having a flexible conduit extending therefrom, with a safety seal comprising a sheet of fibrous material formed to provide a sheath for said conduit to completely enclose the same, a portion

of said sheet extending from the open end of said sheath and having an anchoring portion formed integrally therewith, and means to secure said anchoring portion to said fire extinguisher whereby to maintain said sheath in relative position on said conduit and permit of facile removal therefrom by tearing.

FRED FREDRIKSEN.
